(57) CLAIM

The ornamental design for a swing trainer with attachment as shown and described.

DESCRIPTION

FIG. 1 is a first perspective view of a swing trainer with attachment showing a new design;

FIG. 2 is a second perspective view thereof;

FIG. 3 is a right view thereof;

FIG. 4 is a left view thereof;

FIG. 5 is a top view thereof;

FIG. 6 is a bottom view thereof;

FIG. 7 is a front view thereof; and,

FIG. 8 is a rear view thereof.

1 Claim, 4 Drawing Sheets
